UNITED STATES PATENT OFFICE.

GEORGE BAEHR, OF CORAOPOLIS, PENNSYLVANIA.

DEFORMED BAR.

Application filed July 22, 1919. Serial No. 312,494.

To all whom it may concern:

Be it known that I, GEORGE BAEHR, a resident of Coraopolis, in the county of Allegheny and State of Pennsylvania, have invented a new and useful Improvement in Deformed Bars, of which the following is a specification.

This invention relates to a reinforcing bar for use in concrete constructions. The 10 objects of the invention is to provide a bar for this purpose so formed that the strong coarse particles of the aggregate and not merely the weak grouting can come into intimate contact with large wedge shaped 15 surfaces on the bar, whereby the bar is more efficiently anchored in the concrete; to provide a bar which is of substantially uniform cross section throughout, and one which is easy to roll, by means of rolls in which the 20 grooves are not subject to as much wear and abrasion as the grooves for forming deformed bars heretofore made.

In the accompanying drawings Fig. 1 is a side view of the preferred form of the 25 bar; and Figs. 2, 3 and 4 are cross sections taken respectively on the lines 2—2, 3—3, and 4—4, Fig. 1.

As shown in the drawings the bar is provided with portions 1 and 2 which are 30 polygonal in cross section, the drawings showing the same as substantially square in cross section and the alternate portions 1 and 2 displaced (circumferentially of the bar) relative to each other at an angle of approximately 45° so that a diameter between opposite flat faces 3 of the portions 1 are substantially in the same plane (longitudinally of the bar) as diameters between opposite angles 4 of the portions 2, and 35 likewise, the diameters between opposite flat faces 5 of the portions 2 are substantially in the same plane as diameters between opposite angles 6 of the portion 1. Adjacent square portions are connected by transition 40 sections or portions 7 which, in the embodiment illustrated, are octagonal in cross section, that is, formed of a series of wedge-shaped faces, such as the faces 8 which slope from the ends of the flat faces 3 of the sections 1 and merge into the angles 4 of sections 2, and reversely arranged wedge-shaped faces 9 which slope from the flat faces 5 of sections 2 outwardly and merge into the angles 6 of the sections 1. These wedge-shaped 45 faces are of considerable length, as shown,

and form inclined shoulders or abutments to resist movement of the rod longitudinally in the concrete. The large surfaces, and particularly the gradual sloping wedge-shaped surfaces shown permit the strong 60 coarse particles of the aggregate, such as the coarse pebbles of gravel or the coarse portions of broken stone, to come into intimate contact therewith, so that under tension of the bar these wedge faces press against 65 these strong large particles of the aggregate.

In all forms of deformed reinforcing bars heretofore used, the main body has been provided with closely spaced ridges or 70 grooves arranged either longitudinally, transversely or diagonally of the bar, as a consequence of which the large strong particles of the aggregate do not come into intimate contact with the shoulders or abutments, but only the finer portions of the 75 cement and the grouting comes into contact with such surfaces. The result is that the weak grouting only is put under shear stresses. With the improved bar, however, 80 the shear stresses act directly against the strong coarse particles of the aggregate, and put the concrete under compression stress chiefly.

Furthermore, the bar described is of substantially uniform cross sections throughout, as a result of which 100% of the metal 85 thereof is used for tensile strength. As distinguished from prior bars in which a certain percentage of the metal is used for 90 bonding alone.

Furthermore, the roll grooves for forming the improved bars are of relatively uniform section, not presenting any abrupt depressions or projections which quickly become abraded or worn off by the hot metal when rolling. Consequently rolls for forming the improved bar last much longer than rolls for producing reinforcing bars of the 95 form heretofore used.

It is obvious that modifications can be 100 made in the cross sectional shape of the bar and in the length of the various sections and the proportions and shape thereof without departing from the invention.

I claim:

1. A reinforcing bar for concrete having portions thereof square in cross section, successive portions also square in cross section and turned at 45° to the first portions, and 110

transition portions between said square sections, said transition portions being octagonal in cross section and of substantially the same area in cross section as the square portions.

2. A rolled reinforcing bar for concrete having portions thereof substantially square in cross section, successive portions also substantially square in cross section and turned 10 at 45° to the first portions, and transition portions between said square sections, said transition portions being of substantially the same area in any cross section as the square portions.

3. A rolled reinforcing bar for concrete having portions thereof rectangular in cross section, successive portions also rectangular and of substantially the same area in cross section and turned at 45° to the first portions, and transition portions between said successive rectangular sections, said transition portions being of substantially the

same area at any cross section as the cross section of the rectangular portions.

4. A rolled reinforcing bar for concrete, 25 formed into a succession of non-circular body portions with intermediate transition portions, each of said body portions having its median planes extending through the axis of the bar and positioned at an angle 30 to corresponding median axial planes of the two adjacent body portions, the bar at all points being of substantially the same area in cross-section, the exterior of the bar being shaped to provide a non-straight surface-intersection line by any axial plane of the bar. 35

In testimony whereof, I have hereunto set my hand.

GEORGE BAEHR.
